(57) **CLAIM**

The ornamental design for a log splitting device, as shown and described.

DESCRIPTION

FIG. 1 is a front perspective view of a log splitting device; FIG. 2 is a rear elevation view thereof;

FIG. 3 is a left elevation view thereof;

FIG. 4 is right elevation view thereof;

FIG. 5 is a front elevation view thereof;

FIG. 6 is a top plan view thereof;

FIG. 7 is a bottom plan view thereof;

FIG. 8 is an enlarged detail front perspective view thereof; and,

FIG. 9 is an enlarged detail perspective view of an alternative embodiment.

The broken lines showing a log splitting device are included for the purpose of illustrating environment and form no part of the claimed design.
